ATTORNEY

UNITED STATES PATENT OFFICE.

ALBERT S. FILSON, OF SAN DIEGO, CALIFORNIA.

VIOLIN-TAILPIECE.

1,369,092.

Specification of Letters Patent.

Patented Feb. 22, 1921.

Application filed April 14, 1920. Serial No. 373,754.

To all whom it may concern:

Be it known that I, ALBERT S. FILSON, a citizen of the United States, residing at San Diego, in the county of San Diego and State 5 of California, have invented certain new and useful Improvements in Violin-Tailpieces, of which the following is a specification.

My invention relates to violin tail pieces and the object of my invention is primarily 10 improvements over a patent to myself for violin attachments issued from the United States Patent Office March 9, 1897, Patent Number 578,396 and the objects of the improvements are: First, to provide a means 15 for supporting the *e* string of a violin which will hold it in tension its full length and provide for taking it up at the end where it is most liable to wear because of usage which means may be easily, cheaply and eco- 20 nomically manufactured; second, to provide a more simple and efficient device for the purposes set forth; third, to provide a device of this class which is more durable and which will not so readily deteriorate or 25 get out of order.

With these and other objects in view as may appear hereinafter my invention consists of certain novel features of construction combination and arrangement of parts 30 and portions as will be hereinafter described in detail and particularly set forth in the appended claims reference being had to the accompanying drawings and to the characters of reference thereon which form a part 35 of this application in which:

Figure 1 is a perspective view of a fragmentary tail end portion of a violin showing my improved tail piece mounted thereon in position for use; Fig. 2 is a top or plan view 40 of the tail piece complete with a fragmentary portion of the strings in position thereon on an enlarged scale; Fig. 3 is a side elevational view thereof; Fig. 4 is a sectional view through 4—4 of Fig. 2 and Fig. 5 is a 45 sectional view through 5—5 of Fig. 2.

Similar characters of reference refer to similar parts and portions throughout the several views of the drawings.

The main supporting member 1, reel 2, 50 latch 3 and supporting pin 4 constitute the parts of my violin tail piece. The main supporting member 1 is of the conventional shape and form, except that it is provided with an integral upwardly extending circular lug portion 1^a which is provided with 55 an annular groove 1^b therein and with a

transverse, dovetailed slot 1^c in its normally upward end in which is reciprocably mounted a conforming dovetail shaped latch member 3 adapted to move endwise in said slot but preventing its removal upwardly. It is provided with a central lug portion to facilitate its movement by hand. Revolubly mounted around this lug portion 1^a is a reel member 2 which is supported in position 60 thereon by means of a pin 4 which passes through the side wall of said reel and its middle portion extends into the slot 1^c thus preventing its movement upwardly on said lug member but permits its revoluble move- 65 ment thereon thus supporting the one side thereof. The other side of said reel is provided with a hole 2^a adapted for the end of the *e* string of the instrument to pass through and the end of this string forms a 70 support for the other side of the reel from the pin 4 for holding it in position on said lug. This reel is provided with a plurality of recesses 2^b. In this case I have shown three into which the ends of the latch 3 are 75 adapted to protrude for supporting the reel in position. The *e* string of the violin is wound upon this reel preferably from the lower side up and then back to the lower side again, then passes through the slot 1^c 80 in the support 1 and the free end of the string passes over the violin supports in the usual manner and is secured to the head end of the violin in the ordinary manner. It will be noted that this reel may be turned and 85 let out the *e* string of the instrument as desired and supported by the latch 3, engaging the notches 2^b in the reel so that when the end of the string wears that portion may be 90 cut out, the reel released and a portion of 95 the string unwound and the end fastened again and that the part wound on the reel is held taut and in tension so that it does not have to be stretched and adjusted when in use.

It is obvious that with this construction there is provided a tail piece in which the main support may be molded preferably of hard rubber with the lug in position and forming an integral portion thereof thus 105 providing for the easy and ready manufacture of the tail piece; that there are only four pieces, all of which can be manufactured from hard rubber which is the preferable construction and that each piece is so 110 constructed and shaped that they may be readily molded.

Having thus described my invention what I claim as new and desire to secure by Letters Patent is:

1. A stringed instrument tail piece, provided with an extended integral circular lug provided with an annular slot surrounding its base, a reel revolubly mounted on said lug and a latch member reciprocably mounted in a notch in said lug portion adapted to engage notches in said reel for supporting it against revoluble movement.
- 10 2. A stringed instrument tail piece, provided with an extended integral circular lug

provided with an annular slot surrounding its base and a dovetailed slot transversely 15 therein, all molded of hard rubber, a reel revolubly mounted on said lug provided with a plurality of notches therein and a latch member reciprocably mounted in said dovetailed slot in said lug adapted to engage 20 one of the notches in said reel for supporting said reel against revolution.

In testimony whereof, I have hereunto set my hand at San Diego California this 7th day of April 1920.

ALBERT S. FILSON.
